A. RANCOUR.
SASH HOLDING AND LOCKING DEVICE.
APPLICATION FILED OCT. 15, 1921.

1,433,415.

Patented Oct. 24, 1922.

UNITED STATES PATENT OFFICE.

ALPHONSE RANCOUR, OF FIFE LAKE, MICHIGAN.

SASH HOLDING AND LOCKING DEVICE.

Application filed October 15, 1921. Serial No. 507,945.

To all whom it may concern:

Be it known that I, ALPHONSE RANCOUR, a citizen of the United States of America, residing at Fife Lake, in the county of 5 Grand Traverse, in the State of Michigan, have invented certain new and useful Improvements in Sash Holding and Locking Devices, whereof the following is a specification.

10 This invention relates to a simple device applicable to a window casing and adapted to serve as a lock for the window sash in closed position and as a holder therefor in different elevated open positions.

15 The object of the invention is to provide a device of this character of extreme simplicity and economy of manufacture and facility of application and use.

Figure 1 of the accompanying drawings 20 represents an inside elevation of fragments of a window casing and sashes showing this sash lock and holder locking the lower sash in closed position.

Fig. 2 represents a vertical section on line 25 2-2 of Fig. 1.

Fig. 3 represents a vertical section adjacent to the edge of the lower window sash taken through the bolt holes thereof, and showing the sash holder and lock in neutral 30 position in full lines, in locking position in dash lines and in holding position in dotted lines.

Fig. 4 represents a similar vertical section showing the lower sash in wide open position 35 and the lock-holder engaging the bottom thereof.

Fig. 5 represents a perspective view of this combined sash holder and sash lock.

The same reference numbers indicate corresponding parts in the different figures.

The drawings illustrate this improved combined sash lock and sash holder 10 applied to a window casing 20 in position to lock the lower sash 30 or to hold said sash 45 in open position at different heights.

This duplex device comprises in its preferred embodiment a body 10 composed of a single piece of plate metal adapted to be pivoted to a window casing and to swing 50 thereon into three different positions in relation to the adjacent window sash as indicated in Fig. 3, namely, a locking position for fastening the sash closed, a holding position for suspending it open and a neutral

position in which the sash is permitted to 55 slide up and down without interference.

The body or plate 10 is provided with a central pivot hole 11 adapting it to swing on a pivot stud on the window casing inside of the sash. The upper portion of this plate 60 has an upward straight inner face 12 extending above said pivot hole and adapted to lie flat against the sash in one position of the plate; and the lower portion has a downward straight inner face 13 extending below said 65 pivot hole and adapted to lie flat against the sash in another position of said plate, these inner faces being disposed at an obtuse angle to each other. The upper end of this obtuse angled body is provided with a 70 locking lug 14 disposed at right angles to the upward straight inner face 12 and adapted to engage the lower sash for locking it in closed position. The lower end of this obtuse angled body is provided with a holding 75 stud 15 projecting from the lower end of said downward inner face at right angles thereto and adapted to engage any one of a series of socket holes 31 disposed at different heights on the sash. The lug 14 and stud 15 80 project from said inner faces of the plate in the same general direction therefrom. The straight inner faces 12 and 13 lying flat against the sash in the respective locking and holding positions of the plate assist in 85 holding the plate in fixed position in its locking adjustments. These holes are provided with metal eyes which may be in the form of a metal plate 32 having slots registering with said holes.

90 The plate 10 is secured to the window casing by means of a pivot stud or a pivot screw 19 which is passed through the hole 11 of said plate and takes into the window casing adjacent to the window sash. The plate is 95 adapted to swing on said pivot stud. The pivot stud is preferably so located on the window casing in relation to the window sash and the swinging lock holder that the locking lug 14 will shut over and engage the 100 top of the window sash in closed position thereof.

105 The following is a statement of the manner of using this device: When the lower sash is closed the upper portion of the body 10 is swung towards the sash and the locking lug 14 thereof engages the sash so as to lock it in down position, preferably by shutting

over the top of the sash and the straight edge 12 thereof lies flat against the face of the sash and tends to maintain the locking position. This combined lock and holder is located on the window casing where it is hidden by the side rail of the sash from observation from the outside of the window.

When the sash is to be lifted the plate 10 is swung into the intermediate neutral position shown in full lines in Fig. 3, whereby the locking lug 14 is withdrawn from the sash and both the lugs 14 and the stud 15 are out of contact therewith approximately on a line with the apex 18 of the plate, permitting a free upward movement of the sash. When the sash is lifted to the desired height, the lower portion of the body 10 is swung towards the sash and the holding stud 15 engages one of the holes 31 and holds the sash in elevated open position. When it is desired to lift the window wide open, the locking stud 15 is swung under and made to engage the lower rail of the sash as shown in Fig. 4.

This device may be stamped or drop forged complete from sheet steel, iron or other suitable metal and thus it may be produced very economically.

I claim as my invention:

30 1. An article of manufacture adapted to serve as a combined sash lock and sash holder and consisting of a plate having a central pivot hole adapting it to swing on a pivot stud on the window casing inside the sash, said plate having an upward straight inner face extending above said pivot hole and adapted to lie flat against the sash in one position of said plate and a downward straight inner face disposed at 40 an obtuse angle to said upward inner face, extending below said pivot hole and adapted to lie flat against the sash in another position of said plate, a locking lug projecting from the upper end of said plate at right angles to said upward inner face and adapted to engage the lower sash for locking it in closed position and a holding stud projecting from the lower end of said plate at right angles to said downward inner face and adapted to engage one of a se-

ries of socket holes in the sash, said stud and lug projecting from said inner faces of the plate in the same general direction therefrom.

2. A combined sash lock and sash holder 55 comprising a plate adapted to be pivoted to a window casing inside the sash and including upper and lower members disposed at an obtuse angle and having straight inner faces, the upper member being provided 60 with a locking lug projecting from its inner face at right angles thereto and adapted to shut over the top of the window sash in closed position thereof, and the lower member being provided at its lower end with 65 a holding stud projecting from its inner face in the same general direction as the locking lug and adapted to engage sockets in the window sash for holding the latter in elevated position, and a means for pivoting said plate on the window casing to swing thereon into position to bring the locking lug into engagement with the window sash for locking the sash shut and into 70 position to bring the holding stud into engagement with a socket in the sash for holding the sash open, and into neutral position for permitting the sash to move up or down without engagement of either lug or stud.

3. In a sash fastener and holder the combination of a window casing, a sliding window sash provided with a series of socket holes on its inner face near one edge, and a combined sash lock and sash holder consisting of an obtuse angled plate pivoted 80 to said window casing adjacent to said sash and provided at its opposite ends with lugs projecting in the same direction towards said casing, said plate being adapted to swing into position to bring the upper lug 85 into engagement with said sash for locking it in closed position, and to swing into position to retract said upper lug and bring the lower lug into engagement with one of said sockets for holding the sash in open 90 position at different heights, and into neutral position for permitting the sash to move up or down without engagement of either lug.

ALPHONSE RANCOUR.
